US0D1100799S

(12) **United States Design Patent** (10) Patent No.: **US D1,100,799 S**
(45) Date of Patent: ** Nov. 4, 2025

(54) **CONSOLE**

(71) Applicant: **VOLVO CAR CORPORATION**, Gothenburg (SE)

(72) Inventor: **Chen Li**, Gothenburg (SE)

(73) Assignee: **Volvo Car Corporation**, Gothenburg (SE)

(**) Term: **15 Years**

(21) Appl. No.: **29/934,003**

(22) Filed: **Mar. 22, 2024**

(30) **Foreign Application Priority Data**

Sep. 28, 2023 (EM) 015035562-0012

(51) LOC (15) Cl. **12-16**

(52) U.S. Cl. **D12/415**
USPC .....

(58) **Field of Classification Search**
